ROAD TREATING APPARATUS

Henry A. Ingalls, Bakersfield, Calif.

Application May 17, 1932. Serial No. 611,905

6 Claims. (Cl. 94—39)

My invention relates to road treating and surfacing apparatus, and is particularly directed to a further development of the invention disclosed and claimed in my co-pending application Serial No. 591,404, filed February 6, 1932.

An object of the invention resides in the provision of an organization of road treating and surfacing mechanisms which will thoroughly condition the soil preparatory to the application thereto of a solution such as oil or the like and which will break up and prime the soil so that same will be rendered suitable for immediate application thereto of said solution.

A still further object of the invention is to provide means in the organization for causing trash and objectionable matter to be deflected to one side of the path of movement of the solution distributing mechanism, which latter constitutes an important part of my invention.

Another object of the invention is to provide a group of respective road treating mechanisms which may be made to adapt themselves to respectively varying road conditions. That is to say, should the nature of the soil be such that it is not properly susceptible to the action of one of the mechanisms employed, another one of the mechanisms may be promptly thrown into action. It often happens that in road building portions of the soil under treatment are of a rocky nature and that still other portions are composed mostly of dirt with little or no rock. And in still further instances, the surface under treatment consists rather uniformly throughout a great distance of intermixed parts of soil and small rocks. These conditions must be anticipated, and it is because thereof that I have combined in one complete organization several mechanisms which are intended to be brought into play either singly or together, as the exigency of the occasion demands.

With the above and other objects in view, as will appear hereinafter, my invention relates to certain novel features of construction, combination and arrangement of parts as will be hereinafter described in detail and particularly set forth in the appended claims, reference being had to the accompanying drawings and to the characters of reference thereon which form a part of this application and in which

Figure 1 is a top plan view of my complete organization;

Figure 2 is a vertical longitudinal section therethrough;

Figure 3 is a bottom plan view of one of a plurality of shoes embodied in the invention;

Figure 4 is a section on line 4—4 of Figure 2. In practice, I employ a substantially rectangular frame 5 which consists of suitably spaced apart longitudinal beams or runners 6, 6, transverse bars 7, 7, and an operator's platform 8, the latter located at the extreme rear end of the machine. The bottom surfaces are preferably faced with steel wear strips 9. Operatively journaled in the beams 6, 6, is a crank shaft 10, the same having its crank arms 11 extended to positions outwardly of the beams where they support ground wheels 12. The said shaft is provided with a worm pinion 13 and meshing therewith is a worm screw 14, the latter carried by a shaft 15 journaled for rotation in the bracket 16 of said frame. It is in this manner that proper provision is made for determining to some extent the depth of penetration of the respective road treating implements which I shall describe presently. The arrangement is, further, of such form that the entire set of implements can be raised entirely above the ground line, as would be desirable when transporting the machine from one place to another.

At the front end of the machine is a road scratching or scarifying mechanism 17, which I have so designed and constructed as to render it effective as a scraper and deflector which functions to laterally deflect all large particles, loose stones, trash and the like from the effective path of those respective mechanisms which trail behind same. This mechanism consists of a substantially V-shaped steel strap whose forwardly inclined side bars 18 come together at 19 at the longitudinal center of the frame 5, at which latter point I support a scratching or scarifying tooth 20. Similar teeth 21 are mounted at equi-distant points on the arms 18, there being in the present illustration but two thereof on each arm. Each of the teeth 20 and 21 is suitably clipped to the aforementioned steel strap of the mechanism 17. It follows therefrom that these teeth operate to scratch into the surface as a preliminary step in the treatment of a road surface and that because of the angular positions of the arms 18 all heavy objectionable matter will be cast aside to a position beyond the path of travel of the respective mechanisms which are employed to complete the treatment of the surface.

Behind the mechanism 17 is a gang of cultivator disks 22, all of which are mounted to rotate on a vertically adjustable frame 23. This frame is supported in guides 24 and the former is adapted to be adjusted in a vertical direction,

- by means of handscrews 25. The said guides 24 are mounted on the runners 6—6 and same rise from the upper faces thereof. Now, it is important to note that the disks slant from the vertical and that the frame 23 extends diagonally from one side of the runners to the other thereof; that the disks are equal in number to the respective teeth 20 and 21, and that each tooth is alined with one of the disks. It is also important that it be noted that the disks 22 are capable of vertical adjustment to an extent that same will freely penetrate the soil after the latter has been weakened or broken by the aforementioned teeth. Carried by the frame 23 is a manifold 23a from which fluid distributing tubes 23b extend so as to occupy positions between the adjacent disks 22. Fluid is intended to be delivered to the manifold 23a through the tubes 23c. Immediately behind the disks 22 is a scraper bar or leveler 27 which works in elongated horizontal openings 28 formed in the runners 6, the openings being of such size that stones may find exit therefrom as the bar is advanced over the road.
- Located behind the scraper 27 is a second mechanism for delivering a road treating solution such as oil to the soil after the latter has been fully prepared to receive same. This mechanism, which I have indicated generally by the numeral 29, comprises a cross beam 30, pivoted at 31 on the frame 5 to swing vertically and adapted when in the vertical position shown in Figure 2 to contact with a stop plate 31a, the latter secured between the runners 6. Located above the platform 8 is an oil tank 32 and leading away from same is a flexible tube 33 which connects with a valved cross-head 34. Said cross-head is formed with tubular extensions 35 which carry hollow-distributing members 36, there being as many of said members as there are disks 22, and, as illustrated, same are longitudinally alined with the respective disks 20 and 21. These members are adapted to be adjusted vertically on the beam 30 and to make this possible same are detachably strapped to said beam by clips 37.
- It follows from what has been said that the members 36 may be adjusted to proper vertical positions as may be required to cause their lower ends to penetrate the soil to the desired depth and to trail the disks and function in the furrows made thereby. A distributing mechanism, such as the one just referred to, may be satisfactorily operated in soil that is comparatively free from large rocks and in some instances it may be made to function in conjunction with another oil distributing mechanism which I shall now describe.
- Located rearwardly of the mechanism 29 is an oil distributing mechanism 38, the same consisting of a plurality of identical shoes 39, there being four thereof in the present illustration, and same are staggered with respect to the distributing members 36. Each of these members consists of a casting 40 whose forward end is freely pivoted to a shaft 41 carried by the runners 6. To each of the castings are secured spaced apart arcuate blades 42, 42. The rear portion 43 of each casting is formed with a vertical channel 44 and leading thereto is the lower end of a flexible tube 45, the latter having connection with a valved cross head 46 to which oil from the tank 32 may be supplied by way of a hose 47. Mounted in brackets 48 on the runners 6 is a rocker shaft 49, the latter carrying a lever 50 which leads back to the platform 8, where it may be conveniently actuated as desired. At one end of

the shaft 49 is an arm 51 and extending between same and the lever so as to move with the latter is a rod 52. Extending between the respective shoes 40 and the red 52 are flexible connections 53 by means by which all of the said shoes can be raised to inactive positions above the lower faces of the runners 6 or to any desired position of vertical adjustment as may depend upon the depth of their penetration to be effected. This distributing mechanism is so formed and constructed that each shoe 40 will freely adapt itself to the conditions of the soil and any one thereof may readily pass over any obstruction which shall reside in its path. This said mechanism may be employed exclusively or it may be used in operative conjunction with the mechanism 29 first above referred to. The desirability for so doing may depend entirely upon the nature of the surface under treatment. When used with said mechanisms 23 and 29, same combines therewith to effect a most complete distribution of oil to the soil. The lever 50 is designed to co-act with a suitable keeper device by means of which the shoes 40 may be held in their positions of vertical adjustment.

It is to be understood that it is intended that the machine be drawn over the ground in any well known manner, such, for instance, as by means of a tractor, not shown.

Each of said shoes 39 is formed with a table or ledge 51 to which weights, not shown, may be strapped so that in those instances where it may be found necessary sufficient loads may be imposed upon the shoes to effectively cause same to be retained in the soil and at such depth therein that will insure proper distribution of the oil. With further reference to the said shoes, it will be noted that due to the manner of flexibly mounting same, provision is made whereby they will automatically compensate themselves to irregularities in the surface over which they are compelled to travel. It will be further noted that while each of the shoes is independently movable; they may be simultaneously elevated to any desired position with respect to the lower surfaces of the runners 6.

From the foregoing, it follows that I have made provision for first scratching the surface of the soil so as to prepare same for the effective action of the disks 22, it being intended that the latter cut into the soil and turn same simultaneously with the operation of delivering oil into the furrows cut thereby, thus effecting a very complete distribution of the oil to the soil in advance of further and more complete treatment thereof by the mechanisms 29 and 38 which follow in the path of said disks. The soil when treated in this preliminary manner is then leveled by the action of the trailing bar 27, and all large rocks are deflected from the path to be taken by the said mechanisms 29 and 38.

I claim as my invention:

1. A road treating machine comprising a portable frame adapted to be drawn over the ground, a substantially V-shaped member at the front of the frame, vertically adjustable teeth carried by the member, a disk gang carried by the frame and including disks corresponding in number with the aforementioned teeth and arranged in longitudinal alinement therewith, means for raising and lowering the frame, and means carried by the frame and positioned rearwardly of the said gang of disks for following in the furrows formed by the disks and for distributing a soil treating fluid thereto.

2. A road treating machine comprising a portable frame adapted to be drawn over the ground, a substantially V-shaped member at the front of the frame, vertically adjustable teeth carried by the member, a disk gang carried by the frame and including disks corresponding in number with the aforementioned teeth and arranged in longitudinal alignment therewith, and means carried by the frame and positioned rearwardly of the 10 said gang of disks for following in the furrows formed by the disks and for distributing a soil treating fluid thereto.

3. A road treating machine comprising a portable frame adapted to be drawn over the ground, a substantially V-shaped member located at the front of the frame, a plurality of equi-distantly spaced scratching teeth carried by the member, a plurality of cultivator disks carried by the frame, the said disks arranged in alignment with the respective teeth, means for adjusting said teeth vertically, a plurality of soil penetrating fluid distributors carried by the frame, said fluid distributors corresponding in number with the aforementioned cultivator disks, and a leveling bar carried by the frame and situated between the said fluid distributors and said cultivator disks and at a point with respect to the bottom of the frame so as to come in scraping contact with the soil during propulsion of the machine.

4. A machine of the class described comprising a portable frame, soil ripping means carried by the

frame, and independently tilting fluid distributing shoes mounted on the frame to trail said ripping means, said shoes each consisting of an arcuate portion having a fluid feeding channel for conducting fluid to the soil from the lower edge of the shoe, means for delivering fluid to the channels of said shoes, and means for simultaneously raising and lowering said shoes.

5. A machine of the class described comprising a portable frame, soil rippers carried by the frame, fluid distributors flexibly supported by the frame rearwardly of the said rippers and consisting of identical shoes, each of said shoes including a casting to which arcuate spaced apart blades are secured, means for simultaneously raising and lowering all of the shoes, and means for delivering a road treating solution to the channels of the shoes.

6. A road treating machine comprising a portable frame adapted to be drawn over the ground, vertically adjustable teeth carried by the frame and spaced apart from each other transversely of the frame, a disk gang carried by the frame and including disks corresponding in number with the aforementioned teeth and arranged in longitudinal alignment therewith, and spaced apart fluid distributors carried by the frame and disposed with respect to said disks so as to enter the furrows formed thereby and for distributing a soil treating fluid to said furrows.
